CLAIM

I claim the ornamental design for a side member for a sofa or the like, as shown and described.

DESCRIPTION

FIG. 1 is a rearward left side perspective view of a side member for a sofa or the like of my design.

FIG. 2 is a frontward right side perspective view of the design of FIG. 1.

FIG. 3 is a bottom view of the design of FIG. 2.

FIG. 4 is a front view of the design of FIG. 2.

FIG. 5 is a right side elevational view of the design of FIG. 2.

FIG. 6 is a rear view of the design of FIG. 2.

FIG. 7 is a left side elevational view of the design of FIG. 2; and,

FIG. 8 is a top view of the design of FIG. 2.
